Primary Examiner — Mary Shannon Malley*Assistant Examiner* — Michelle Marquart Christeon(74) *Attorney, Agent, or Firm* — Daniel M. Cohn;
Howard M. Cohn(57) **CLAIM**

The ornamental design for a seat, as shown and described.

DESCRIPTION

FIG. 1 is a perspective view of a seat showing my new design;

FIG. 2 is a another perspective view thereof;

FIG. 3 is a front view thereof;

FIG. 4 is a back view thereof;

FIG. 5 is a left view thereof;

FIG. 6 is right view thereof;

FIG. 7 is top plan view thereof;

FIG. 8 is bottom plan view thereof; and,

FIG. 9 is an enlarged view of FIG. 2.

The long-dash short-dash broken lines in FIGS. 2 and 9 represent the bounds of the enlargement taken from FIG. 2 and forms no part of the claimed design. The dash-dash broken lines illustrate portions of the seat that form no part of the claimed design.

1 Claim, 9 Drawing Sheets(56)
